UNITED STATES PATENT OFFICE

WILLIAM THOMAS BUCKINGHAM ROBERTS AND HARRY HARDY JACKSON, OF LEICESTER, ENGLAND, ASSIGNEES TO UNITED SHOE MACHINERY CORPORATION, OF PATERSON, NEW JERSEY, A CORPORATION OF NEW JERSEY

MACHINE FOR APPLYING TAPE TO SHEET MATERIAL

Application filed May 25, 1929, Serial No. 368,057, and in Great Britain June 9, 1928.

This invention is concerned with improvements in machines for applying tape to sheet material and is herein illustrated and described as embodied in a machine for applying adhesive tape to boot or shoe uppers.

Such uppers generally comprise two parts united together by a seam (usually called the "back" seam) which seam extends, in the finished boot or shoe, up the back thereof from the heel seat to the top of the upper.

The margins of the two parts where they are joined by the seam necessarily stand up from the body of the upper along the length of the seam due to the presence of the seam and form a ridge, and it is desirable that this ridge shall be flattened down somewhat in order that it shall not chafe the foot of the wearer. It is also desirable, for the same reason and also to strengthen the seam, to cover the ridge by a tape secured to the parts of the upper on the respective sides of the seam close to the latter, the tape overlying the seam ridge along the length thereof. In the United States Letters Patent No. 1,646,212, granted Oct. 18, 1927, upon an application filed in the name of Walter P. Osgood, and in the British Patent No. 297,349, there are described machines which may be used to operate upon a boot or shoe upper along the back seam to press the seam ridge to flatten it while applying adhesive tape along and over the seam, the flattening of the seam ridge and the application of the tape being effected in a single operation and by the same instrumentalities, which include a presser having an oscillatory movement.

According to the present invention novel and improved means are provided in a taping machine for effecting both the flattening of the seam and the said taping.

In one of its several aspects the present invention provides a machine having means for flattening the seam ridge and other means for applying the tape therealong only after

it has been so flattened. The tape applying means may comprise a roll.

In another of its several aspects the present invention provides in one and the same machine means for performing operations of seam pressing and tape applying continuously and uninterruptedly throughout the length of a seam. That is to say, seam pressing and tape applying means operate continuously upon the work during the whole of such time as the latter is presented to them. This enables the seam pressing and tape applying operations to be effected in the minimum of time and therefore allows separate pieces of work to be fed to the operating means in quick succession.

In still another of its aspects the invention provides a machine comprising a plurality of rotary tools, one of which guides the work in a direction lengthwise of the seam, another of which rubs down the seam ridge, and another of which applies the adhesive tape to the seam.

The invention will be readily understood from the following description, reference being made to the accompanying drawings, in which,—

Fig. 1 is a front elevation of the said machine;

Fig. 2 is a side view partly in section and on an enlarged scale showing the relative positions of certain parts of this machine;

Fig. 3 is a plan view of the parts shown in Fig. 2;

Fig. 4 is a detail view on a still larger scale showing the formation of one of the parts shown in Figs. 2 and 3; and

Fig. 5 is a plan view of a work support.

The machine now to be described is, save as otherwise indicated, similar to the machine described and illustrated in United States Letters Patent Nos. 1,259,134 and 1,474,350, granted March 12, 1918 and Nov. 20, 1923 upon applications filed respectively in the names of William T. B. Roberts and

Frederick William Farrar, and reference will frequently be made to the former of these specifications throughout the following description. The machine illustrated in the accompanying drawings comprises a frame member consisting of a base 1 and an overhanging arm 3 rising from the right-hand side of the base (viewing the machine from the front) and extending to the left over the base at a considerable height thereabove as shown in Fig. 1. A short main shaft 5 (extending from the right towards the left of the machine) is mounted in horizontal bearings in the base 1, and the right-hand end of this shaft projects beyond the right-hand end of the frame. Fast and loose pulleys 7 and 9 are arranged upon this end of the main shaft, and a belt shifter (not shown) is provided to shift a driving belt from the fast to the loose pulley (or vice versa) as desired. A second horizontal shaft 10 extending from the right towards the left of the machine is mounted in bearings in the overhanging arm and has secured to it at its right-hand end (which projects beyond the frame) a pulley 11 adapted to be driven by a belt from another pulley 13 fast on the main shaft 5 aforesaid. The left-hand end of this second horizontal shaft 10 is, as shown in Figs. 2 and 3, formed as a roll 15 (hereinafter termed the rubbing roll) having longitudinal corrugations on its periphery and which, as described in the aforesaid Letters Patent No. 1,259,134, is some five-eighths of an inch in diameter. A third horizontal shaft 17 (Fig. 2) is mounted in bearings in the top of the overhanging arm substantially over and parallel with the second horizontal shaft 10. The right-hand end of the shaft 17 has a pulley 19 secured to it and a pulley 21 fast on the main shaft 5 is coupled by belting to this latter pulley 19 through reducing pulleys 23, 25 mounted on a countershaft 27 detachably secured to the back of the arm 3. By this means the upper horizontal shaft 17 is driven at a lower speed than is the one 10 immediately below it carrying the rubbing roll 15. The horizontal shaft 17 extends completely across the machine to the left-hand side thereof and carries on its left-hand end, outside the machine frame and as shown in Fig. 5 of the drawings of the Letters Patent last mentioned, a small pinion. This pinion meshes with an idler pinion mounted below it in a stub-shaft secured to the frame. Two smaller pinions are arranged below the idler pinion as shown in the machine of the same Letters Patent and are driven thereby, the said pinions being spaced apart around the lower periphery of the idler pinion, and being adapted, as in the patented machine, to drive the shafts of two of the work engaging rolls.

65 One of said pinions (i. e., the one nearer

to the front of the machine) is secured to a short shaft 29 (see Fig. 3) extending towards the right as viewed in Fig. 1 parallel to the shaft 10 carrying the rubbing roll, the right-hand end of the short shaft 29 lying close to and alongside the rubbing roll 15 on the forward side thereof. A combined seam opening, work-feeding and guiding device more fully described in said Letters Patent No. 1,474,350 is mounted upon the right-hand end of this short shaft 29, said device comprising two smooth conical portions 31, 33 arranged on the shaft with their smaller ends facing each other and with a peripheral rib 35 (formed on the shaft) between the conical portions. The conical portions are slideable on the shaft (but cannot rotate relatively thereto) and are each urged inwardly towards the other and towards the said rib by springs 37, 39 arranged behind them. Each of said conical portions is approximately some twenty-one thirty-seconds of an inch in diameter at its widest part and some seven-sixteenths of an inch at its narrowest part. The rearmost of the two small pinions aforesaid is secured to a shaft similar to that just mentioned but positioned on the other side of the rubbing tool 15 (i. e., the rear side). Fixed upon the right-hand end of this shaft alongside the rubbing tool is a tape-applying roll 41. This tape applying roll is employed in place of the ironing roll referred to in said Letters Patent No. 1,474,350 and differs therefrom in form, consisting of a smooth roll some five-sixteenths of an inch in diameter having two diametrically opposite portions of its periphery flattened as shown at 43 (Fig. 2) to allow the work to be presented easily to the roll and to be manipulated relatively thereto while it is being acted upon by the roll.

A peripheral groove 45 (Fig. 4) (to receive the flattened seam ridge as hereinafter explained) is, however, cut in the cylindrical portions of the roll surface at such a position along the length thereof that its middle is directly in line (when looking at the machine from the front) with the aforesaid peripheral rib 35 forming part of the work-guiding device. The peripheral groove 45 is approximately an eighth of an inch wide and one thirty-second of an inch deep.

A carrier 47 (Fig. 1) for a roll of adhesive tape is mounted on the rear of the machine on the overhanging arm 3 and tape from a roll on the carrier is led from the under side of the roll down a guide 49 positioned over the tape applying roll 41. The tape guide 49 is so positioned with respect to the tape-applying roll 41 that the tape can extend from the guide round the forward side of the roll, overlying the groove 45, and under the underside of the roll as indicated in Fig. 2. The tape guide 49 comprises a pair of side members 51 secured to a bed 53 which is adjust-

ably mounted on a pivoted block 55 (Fig. 2). A thin sheet-metal housing 57 is arranged at the forward end of the guide and the top of this housing is extended forwardly and downwardly as shown at 59 to extend between 5 the rubbing tool 15 and the tape-applying device 41 and prevent the tape from passing over the rubbing tool. A pad 61 of felt is secured to the bottom of the tape guide to bear upon the tape applying tool 41 to clean it. A set screw 63 passing through a downwardly turned end of the guide bears against the pivoted block 55 to limit the position of the guide relatively to the tape applying device. A spring detent 66 in the guide is arranged to press on the tape and to allow the tape to be drawn forward during the operation of the machine; but it prevents the tape running back at the conclusion of the operation, as it is liable to do on account of the tendency of the roll of tape to draw the tape in again when the tape is severed at the end of an operation. The tape guide is rigidly but adjustably secured at the desired height over the tape applying tool on a stud 56 supported in ears projecting from the rear side of the overhanging arm 3.

From the foregoing description it will be evident that as shown in Fig. 2 work fed through the machine from the front will first of all be acted upon by the work-guiding and feeding device 31, 33 and will be fed by the latter to the grooved or corrugated rubbing tool 15 after which it will be fed to the grooved tape applying roll 41 to have the tape only then laid on and pressed securely to it.

In order to support the work while it is being operated upon, a carrier for a work-support is arranged on the base 1 of the frame directly underneath the operating tools substantially as described in Letters Patent No. 1,474,350 aforesaid. The work-support comprises a block 65 which normally occupies an inoperative position below the tools but can be raised by a treadle (not shown) into operative position close to the underside of the tools when work is to be presented to the machine as shown in Figure 2. The upper face of the block 65, upon which the work rests while it is being operated upon, is slightly convex when viewed from the side as shown in Figure 2, and the edges of the upper face are bevelled off at the leading end of the block as shown at 67 for about half the length of the convex face to form a central V-shaped ridge 69 (in the illustrated machine about an inch and a half long) with which the work-guiding and feed roll co-operates and which helps to guide the work as it is being presented to the machine. The rear part of the convex face also has its sides bevelled off as shown at 71 but instead of forming a sharp V ridge as at the forward end they form a V ridge terminating in a narrow, and almost flat,

work-supporting face 73 which is roughly a quarter of an inch wide and about an inch long. The sloping faces of the front V-shaped part of the work support are adapted to co-operate with the conical parts of the work-guiding and feeding member in presenting the work properly to the tools; and the narrow, flat, work-supporting face 73 last mentioned is adapted to support the work while the seam ridge is being rubbed down by the corrugated rubbing tool 15.

The part of the work-support for cooperating with the tape-applying roll 41 comprises a freely rotatable roll 75 (about three quarters of an inch in diameter) mounted in a yoke 77 which is attached as hereinafter described to the rear face of the block 65 aforesaid. The yoke has projecting forwardly from it a stud 79 perpendicular to the roll axis which enters into a substantially horizontal hole in the block; and a slot cut in the face of the stud receives within it a stationary pin 81, there being limited relative freedom of movement between the pin and slot. The arrangement is such that the yoke 77 and therefore the roll 75 carried thereby can tilt about a substantially horizontal axis (that is the stud axis 79) which lies in the vertical plane containing said sharp V ridge 69, to an extent limited by contact of the said pin 81 and slot. The generally convex face of the work support as seen in Figure 2 (i. e., from the side) and the top portion of the periphery of the said roll 75 form a more or less continuous convex face; and the yoke 77 extends across the rear of the roll and is there so shaped as shown at 83 to give an easy lead-off of the work from the roll 75. The convexity of the work support, considered from front to rear of the machine generally, is such that it corresponds roughly to the curvature of the heel end of an upper so that the back seam in the work to be operated upon is supported approximately along the whole length of the work-support. Such convexity corresponds roughly to an arc about three inches long struck with a five inch radius.

The roll 75 (Fig. 5) itself comprises two coaxial cylinders of metal or other rigid material and of equal diameter, screwed together and clamping between them a yielding washer 85, of rubber for example, the periphery of which lies very slightly below the periphery of the roll. This rubber washer is arranged midway along the length of the roll and lies directly underneath the groove 45 in the tape-applying roll 41. The outer ends of the cylindrical parts of the roll are bevelled as shown in Figure 5 to make the peripheral supporting face of the roll generally similar in lateral formation to that of the adjacent part 71, 73 of the work supporting block but leaving the central part of the roll periphery cylindrical for a width of about half an inch, i. e., about the width

of the tape. The width of the rubber washer is about three-sixteenths of an inch, that is to say somewhat greater than the width of the groove 45 in the taping roll 41. The 5 shafts before described which carry the guiding, rubbing and tape-applying rolls are so located that the active portions of said rolls are disposed, when viewed from the side, on a curve similar to that presented by the upper faces of the various parts of the work-supporting means as shown in Figure 2.

The mountings for the guiding, rubbing and tape-applying rolls are so arranged that the rolls may be urged downwardly on to the 15 work by springs; and adjusting means 87 are provided for varying the pressure with which these springs press the tools against the work substantially as described in Letters Patent No. 1,259,134. Moreover the heights 20 of the rolls may be adjusted relatively to each other by adjusting levers 89 by the rotation of which the rubbing tool can be raised or lowered by itself or the work guiding and taping rolls raised or lowered in unison.

The operation of the machine is as follows:—

Assuming the machine to be running (i.e., all the three rolls to be rotating) and the 30 work-support to be in its normal lowered position, the operator raises the latter by means of a treadle (not shown) to its working position. He then takes a piece of work, opens it out and urges its leading edge into the bite 35 between the parts 31, 33 of the combined work-feeding and guiding roll and the work-support 65, the two pieces of work joined by the seam straddling the work-support and the seam itself overlying the V-shaped rib 40 69 thereon. The rib 35 on the work-feeding and guiding roll enters in the gap between the two narrow margins of upper projecting from the seam thereby separating them and 45 serves to guide the work to the rubbing tool, while the pressure on the sides of the seam ridge exerted by the conical members 31 and 33 and the pressure of the roll on the work serve also to feed the latter by friction. The work is passed thereby to the rubbing tool 50 15 by which the seam ridge is rubbed down. The work thereafter passes to the taping roll 41 and, owing to the flattened parts on the taping roll before mentioned, enters readily therebetween. As the work comes under the 55 taping roll the adhesive tape passing around the front of this roll and rearwardly under it is, by the action of that roll, automatically laid on and pressed against and secured to the work on both sides of the already rubbed-down seam parts. The seam ridge, together 60 with that part of the tape overlying it, enters into the groove 45 in the taping roll, and the depth of the groove is so chosen as to be somewhat less than the thickness of the 65 work at the flattened seam ridge plus the

thickness of the tape. The taped work at the seam ridge being thus too thick to be received fully in the said groove, the underside of the work below the seam ridge will be forced against the rubber ring 85 in the supporting roll, and this rubber ring will yield to accommodate the extra material and allow the taping roll to press the tape on the work at each side of the seam parts while also pressing by the bottom of its groove 45 on the tape on top of said seam parts and continuously and uninterruptedly pressing the same notwithstanding the presence of the flats 43. Should the portion of the work at one side of the seam parts be thicker than that on the other, the supporting roll 75 under the taping roll will tilt on the axis of the stud 79 to accommodate itself to this varying thickness and will tend thereby to distribute the pressure evenly over the work 80 on both sides of the seam ridge.

As will have become apparent all the rolls, with the exception of the seam rubbing roll, are smooth: and, owing to the work which the latter has to do in flattening the seam ridge and the consequent resistance offered thereby to the passage of the work through the machine, slippage occurs between the other driven rolls and the work. The work is therefore fed through the machine by the 95 friction of the driven rolls at a speed considerably less than the slowest peripheral speed of any of these rolls.

It is to be understood, however, that all the driven rolls (i.e., those above the work) 100 rotate in the same direction (i.e., anti-clockwise as seen in Figure 2) and they all play some part therefore in feeding the work through the machine while both the seam flattening and the tape-applying are, if not essentially at all events largely, rubbing or wiping operations.

The drawing-off of the tape from the supply is controlled by the passage of the work through the machine, the flattened faces 43 on the tape-applying roll releasing the tape intermittently so as not to feed it too fast; the tension on the tape as it is drawn from the supply also prevents excessive feed of the tape.

We have found that where separate frictional tools are used for applying the tape to the material and for feeding the work and for rubbing down the seam, it is difficult to provide such an arrangement that each tool 110 will perform its particular duty effectively. If one or other of the tools does not operate in proper harmony with the associated tool, then wrinkling of the upper or of the tape or failure of the tape to stick is liable to occur. By forming the tools as above described with reference to the drawings and by so organizing the tool driving means that the rubbing-down roll 15 rotates at approximately two thousand eight hundred revolutions per 115

minute while the work guiding and feeding roll 31, 33 and the taping roll 41 each run at approximately five hundred and forty revolutions per minute, no difficulty has been found under ordinary conditions in feeding the work and the tape non-positively at the correct relative speeds while performing seam rubbing-down as a distinct operation on the work from the taping.

Having thus described the invention, what we claim as new and desire to secure as Letters Patent of the United States is:

1. A machine for applying adhesive tape upon a seam, comprising means for flattening a portion of the seam ridge, and other means operable subsequently to the operation of said flattening means for applying adhesive tape upon said portion of the seam ridge.

2. A machine for applying adhesive tape upon a seam, comprising means operable progressively to flatten the seam ridge, and means positioned behind said flattening means for applying adhesive tape progressively upon the portion of the seam ridge which has already been flattened by said flattening means.

3. A machine for applying adhesive tape upon a seam, comprising means for progressively feeding the work, means operable progressively to flatten the seam ridge as the work is fed, means for guiding adhesive tape over the seam ridge, and means for applying the adhesive tape progressively upon the seam ridge, said flattening means being positioned in advance of said tape applying means in order to flatten the seam ridge before the application of the tape thereto.

4. A machine for applying adhesive tape upon a seam, comprising means for guiding the work along the length of the seam, means for pressing the seam ridge to flatten it, and means for applying adhesive tape along and upon the seam ridge, said tape applying means being operable to apply tape to each portion of the seam ridge only after that portion has been flattened by said pressing means.

5. A machine for applying adhesive tape upon a seam, comprising means for guiding the work along the length of the seam, means for pressing the seam ridge to flatten it, and other means for pressing adhesive tape against the seam ridge continuously and uninterruptedly throughout the passage of the work.

6. A machine for applying adhesive tape upon a seam, comprising a work support, a roll constructed and arranged to bear upon the seam ridge and to press the seam ridge against said work support to flatten the seam ridge, and means for applying adhesive tape to the seam.

7. A machine for applying adhesive tape upon a seam, comprising a driven roll having longitudinal corrugations on its periph-

ery for rubbing down the seam ridge, means for supporting the work against said rubbing roll, and means for applying adhesive tape to the seam over the seam ridge.

8. A machine for applying adhesive tape upon a seam, comprising means for flattening the seam ridge, a roll for applying adhesive tape upon the flattened seam ridge, and a roll for supporting the work against the pressure of said tape-applying roll.

9. A machine for applying adhesive tape upon a seam, comprising means for flattening the seam ridge and a pair of cooperating rolls for applying adhesive tape upon the flattened seam ridge.

10. A machine for applying adhesive tape to a seam having cooperating means for pressing a tape against the seam in a work piece passed therebetween, said means comprising yielding and rigid portions constructed and arranged respectively to operate yieldingly on the seam ridge and to operate positively upon the tape and work piece to press them together at either side of the seam ridge.

11. A machine for applying adhesive tape to a seam comprising means for flattening the seam ridge, and means for pressing an adhesive tape against the flattened seam, said pressing means being constructed and arranged to exert a yielding pressure on the seam ridge and to press the tape and work positively together at either side of the seam ridge.

12. A machine for applying adhesive tape to a seam comprising a pair of cooperating rolls adapted for pressing an adhesive tape against the seam in a work piece, said rolls being constructed and arranged yieldingly to press the tape against the seam ridge and to press the tape at either side of the seam ridge positively against the body of the work adjacent to the seam.

13. A tape applying machine having, in combination, means for flattening the ridge of a seam in a seamed work piece, and means for uniting an adhesive tape with said work piece over the seam comprising cooperating pressing elements one of which is constructed and arranged yieldingly to support the seam ridge and positively to support the portion of the work piece covered by the tape at either side of the seam ridge.

14. A machine for applying adhesive tape upon a seam, comprising a pair of cooperating rolls between which the work may be passed for applying adhesive tape upon the seam, one of said rolls having relatively yielding and rigid peripheral portions at different positions axially of the roll to ensure effective cooperation of the rolls in applying the tape on the seam ridge and also on the work at each side thereof.

15. A machine for applying adhesive tape to a seam comprising a pair of cooperating

- rolls between which work may be passed for uniting an adhesive tape with a seam in a work piece, one of said rolls having a yielding portion arranged to support the work 5 piece opposite the ridge of the seam and rigid portions at either side of said yielding portion for supporting the portion of the work piece covered by the tape at either side of the seam.
- 10 16. A tape-applying machine comprising means for pressing adhesive tape upon a seam, and a roll having a yielding peripheral portion to accommodate the seam ridge and also having a relatively rigid portion on each 15 side of said yielding portion to ensure the effective application of pressure by said pressing means upon the tape on each side of the seam ridge.
17. A machine for applying adhesive tape 20 upon a seam, comprising means for flattening the seam ridge, means for pressing adhesive tape upon the seam, a roll for supporting the work against the pressure of said tape-applying means, and means for mounting said supporting roll constructed and arranged to permit free tilting of the axis of said supporting roll to accommodate inequalities in the thickness of the work on the respective sides of the seam.
- 25 18. A tape-applying machine, comprising means for pressing adhesive tape upon the work, a roll for supporting the work against the pressure of said tape-applying means, and means for mounting said supporting roll constructed and arranged to permit free tilting of the axis of said supporting roll to accommodate inequalities between the various portions of the work in contact with said supporting roll.
- 30 19. A tape-applying machine, comprising a pair of cooperating rolls constructed and arranged to apply adhesive tape to a piece of working passing between, and means for mounting one of said rolls constructed and 35 arranged to permit free tilting of the axis of said roll to accommodate inequalities between the various portions of the work passing between said rolls.
- 40 20. A machine for applying adhesive tape 45 upon a seam, comprising a plurality of rotary tools, one of which is adapted to guide the work in a direction lengthwise of the seam, another of which is adapted to rub down and thereby flatten the seam ridge, and another of which is adapted to apply adhesive tape on the seam, and means for supporting the work in its passage past said tools.
- 50 21. A machine for applying adhesive tape 55 upon a seam, comprising a plurality of driven rolls all rotating in the same direction and each assisting in the feed of the work, one of said rolls being adapted to guide the work in a direction lengthwise of the seam, another of said rolls being adapted to rub down and thereby flatten the seam ridge, and another
- of said rolls being adapted to apply adhesive tape to the flattened seam ridge, and means for supporting the work in its passage past said tools.
22. A machine for applying adhesive tape 70 upon a seam, comprising a roll having a peripheral groove for guiding the work lengthwise of the seam, a driven rubbing roll for flattening the seam ridge, a roll adapted to apply adhesive tape upon the work to cover the flattened seam ridge, and means for supporting the work in its passage past said rolls.
- 75 23. A tape-applying machine, comprising means for feeding the work to which adhesive tape is to be applied, and a member constructed and arranged to exert a wiping action upon the adhesive tape to apply the same to the work.
- 80 24. A tape-applying machine comprising means for feeding the work to which adhesive tape is to be applied, and a member constructed and arranged to apply the adhesive tape to the work, said member being driven in the direction of the feed of the work but at a faster speed so as to exert a 85 wiping action upon the tape.
- 85 25. A machine for applying adhesive tape to a seam comprising means for pressing tape against a seam in a work piece, said means having a groove to accommodate the seam 90 ridge and a yielding surface constructed and arranged to exert a yielding pressure on the seam ridge.
- 95 26. A machine for applying adhesive tape to a seam comprising tape applying rolls, one of said rolls having a groove to receive the seam ridge and having a yielding surface for sustaining the seam ridge against the other of said rolls.
- 100 27. A machine for applying adhesive tape 105 upon a seam, comprising a tape-applying roll having a peripheral groove to receive the seam ridge, and a work supporting roll having a yielding surface for sustaining the seam ridge against said tape-applying roll.
- 110 28. A machine for applying adhesive tape upon a seam, comprising a pair of cooperating rolls for applying the tape, one of said rolls having a peripheral groove to receive the seam ridge and the other of said rolls having a yielding surface opposite said groove of the first-mentioned roll to accommodate any excess thickness of the seam ridge.
- 115 29. A machine for applying adhesive tape 120 upon a seam, comprising a roll constructed and arranged to rub down the seam ridge to flatten it, a roll for pressing adhesive tape on the flattened seam ridge, and means for driving said rubbing roll at a greater peripheral speed than said tape-pressing roll in order to obtain an effective wiping action of said rubbing roll upon the seam.
- 125 30. A machine for applying adhesive tape upon a seam, comprising means for flatten- 130

ing the seam ridge, and means for applying adhesive tape to the work constructed and arranged to press the tape upon a portion of the seam ridge and simultaneously to press the tape upon the portions of the work upon each side of said portion of the seam ridge.

31. A roll for applying adhesive tape upon a seam, said roll having a peripheral groove to accommodate the seam and having a portion of its periphery flattened to facilitate the presentation of work to the roll.

32. In combination with means for applying adhesive tape upon a seam, a work support comprising a member having a ridge adapted to be straddled by the seam for guiding the work lengthwise of the seam, and a roll adjacent to said member for supporting the work against said tape-applying means.

33. In a machine for applying adhesive tape to a work piece having a seam, means for separating the margins of the work piece projecting from the seam, means for flattening the seam ridge, and means for applying adhesive tape to the work over the seam ridge.

34. A machine for applying adhesive tape to a piece of work having a seam comprising means for separating the margins of the work projecting from the seam, means for flattening the margins of the work projecting from the seam, said first-mentioned means also being constructed and arranged to guide the seam to said flattening means, and means for applying adhesive tape to the work piece over the seam.

35. A machine for applying adhesive tape to a work piece having a seam comprising a plurality of rotary tools one of which is adapted for flattening the seam ridge, another of which is constructed and arranged to form a gap between the margins of the work piece constituting the seam ridge and to guide the work as it is presented to said flattening tool, and another of which tools is adapted to apply adhesive tape to the work piece over the seam.

In testimony whereof we have signed our names to this specification.

50 WILLIAM THOMAS BUCKINGHAM ROBERTS.
HARRY HARDY JACKSON.
